Primary Examiner — Susan Bennett Hattan*Assistant Examiner* — Omeed Agilee(74) *Attorney, Agent, or Firm* — Workman Nydegger(57) **CLAIM**

The ornamental design for a remote activation clip, as shown and described.

DESCRIPTION

FIG. 1 is a perspective view of the remote activation clip showing the new design;

FIG. 2 is a front end elevational view of the remote activation clip;

FIG. 3 is a back end elevational view of the remote activation clip;

FIG. 4 is a left side elevational view of the remote activation clip;

FIG. 5 is a right side elevational view of the remote activation clip;

FIG. 6 is a top plan view of the remote activation clip; and, FIG. 7 is a bottom plan view of the remote activation clip. The broken lines shown in the drawings are for the purpose of illustrating portions of the remote activation clip that for no part of the claimed design.
